Filed Mar. 8, 1962, Ser. No. 69,149

Term of patent 14 years

(Cl. D13—1)

The figure of drawing is a front perspective view of a prefabricated house, showing our new design.

The other two sides are substantially like the sides shown in the drawing.

The dominant features of our design reside in the portions shown in full lines on the drawing.

We claim:

The ornamental design for a prefabricated house, as shown and described.
